UNITED STATES PATENT OFFICE.

JAMES RAMSEY SPEER, OF PITTSBURG, PENNSYLVANIA, ASSIGNOR TO BROWNSVILLE GLASS COMPANY, OF PITTSBURG, PENNSYLVANIA, A CORPORATION OF PENNSYLVANIA.

ELECTRIC HEATER FOR GLASS CYLINDERS.

No. 859,280.

Specification of Letters Patent.

Patented July 9, 1907.

Application filed November 23, 1906. Serial No. 344,728.

To all whom it may concern:

Be it known that I, JAMES RAMSEY SPEER, a citizen of the United States, residing at Pittsburg, in the county of Allegheny and State of Pennsylvania, have 5 invented or discovered new and useful Improvements in Electric Heaters for Glass Cylinders, of which the following is a specification.

My invention relates to apparatus for electrically heating wires in contact with glass cylinders as a step 10 in severing the same.

The objects of my invention are to heat glass electrically on predetermined lines for the purpose of capping off the bait from the body of the glass; or for the purpose of severing glass sheets into shorter lengths.

15 Other objects thereof are to provide means for automatically holding the heating wire tightly against the glass; to provide a traveling device for supporting the wire; and to provide means for holding the wire-supporting device in close contact with the cylinder.

20 Other objects will appear hereinafter.

Referring to the drawings which illustrate only one form of my invention, Figure 1 is a side elevation thereof, showing the electric heater in position for capping off the glass from the bait; Figs. 2 and 3, perspective 25 views showing opposite faces of the lower end of the device which carries the heating wire; Fig. 4, a sectional detail of a portion of the pivoted terminal for one end of the heating wire; and Fig. 5, a section on the line 5-5 of Fig. 1.

30 In the drawings, 1 represents a carriage or trolley having the wheels 2 running on the upper and lower edges of the rail 3, and carrying the two contacts 4 and 5, which are in sliding engagement with the trolley wires 6 and 7. I do not restrict myself to the trolley, 35 the track or the movable contacts shown as these may be variously constructed. The trolley 1 is provided with the arm 8 having its lower section 9 hinged on the pin 10 and pressed away from the observer by the coiled spring 11 in a well known manner.

40 12 is an extension or wire-holder on the lower portion of the arm-section 9, said holder having one lateral portion provided with the upward incline 13, and the remaining lateral portion with the downward incline 14, both inclines commencing at the rear face of the holder 45 and extending toward the front thereof or toward the arm 8. These inclines end in the slotted ways 15 and 16 at the front face of the holder 12.

47 17 is the fixed terminal for the heating wire 18 which has one end secured thereto by an eye. From the terminal 17 the wire 18 passes down the incline 13 and along the slot 15 and thence around the glass cylinder 19, through the slot 16 and down the incline 14 to the terminal hook 20, to which it is secured by an eye. The hook 20 is a curved arm on the lever 21 pivoted to

the block 22 secured to the lower end of the arm 8. 55 The lever 21 has an adjustable weight 23 thereon, which acts to keep the wire 18 automatically in contact with the cylinder as the wire stretches under the action of the heat. The hook 20 has its end covered with insulation 24 and carries a contact strip 25 to maintain electric contact with the wire 18 in all positions of the lever 21. The contact strip 25 is connected to the wire 26 which leads up along or through the arm 8 to the sliding contact 4. The terminal 17 is connected by the wire 27 to the sliding contact 5.

55 After a cylinder of glass and the attached bait have been lowered to a horizontal position for capping off the bait, the operation is as follows: The trolley 1 is run along the track or rail 3 until the section 9 of the arm 8 and the wire holder 12 are opposite the place where it is desired to crack off the cylinder. The holder 12 should face the cylinder 19. The wire, which is hooked to the terminal 17, is passed around the cylinder by an attendant and connected to the hook 20, as hereinabove described. A switch is then actuated to close the electric circuit, which is as follows: from a suitable source of electric energy (not shown) through the trolley wire 6, the sliding contact or shoe 4, the wire 26, the contact strip 25, the heating wire 18, which must be of high resistance, the terminal 17, the wire 27, the sliding contact 5, and the trolley wire 7 back to the source of power. The electric current heats the wire 18 intensely, some of its heat being imparted to the contiguous portion of the cylinder. By touching a portion of the heated circle on the cylinder with a cold iron, 70 the bait is readily cracked off. During the heating of the wire 18, it expands, but the expansion is at once taken up by the weighted lever 21, as explained. The slackening of the wire is thus prevented and the holder 12 is automatically drawn toward the cylinder, the hinge 10 permitting the holder to move so as to keep the wire in contact with the whole circumference of the cylinder, whereby it will be uniformly heated. After 75 the bait has been detached from the cylinder, the wire unhooked, and the current switched off, the attendant swings the section 9 of the arm 8 out away from the cylinder so that the rear face of the holder will clear the cylinder, and pushes the trolley along the track until it reaches the proper place to crack off a section of the cylinder, said place being indicated by the dotted line 28 on Fig. 1. The cylinder is cracked off at the line 28 in the same manner that the bait was cracked off.

80 85 Many modifications may be made in my invention and I do not desire to be restricted to specific mechanism except when specific terms are used in the claims. 90 95 100 105 I claim—
1. In an electric heater for glass cylinders, a heating wire adapted to encircle a cylinder, positive and negative

- 2 terminals secured to the respective ends of said wire, and a weighted lever for automatically taking up the expansion of the wire so as to maintain it in contact with the cylinder.
2. In an electric heater for glass cylinders, a heating wire adapted to encircle a cylinder, a terminal block having lateral inclines converging toward one edge of the block, a fixed terminal and a movable terminal arranged so as to maintain the ends of the wire on said inclines, the movable terminal having means for taking up the expansion of the wire during the passage of the electric current therethrough.
3. In an electric heater for glass cylinders, means for electrically heating a cylinder in a circumferential line, and a carriage for supporting said heating means and moving it to any desired place along a cylinder.
4. In an electric glass heater, a carriage, a heating wire, and a support for the wire secured to the carriage.
5. In an electric glass heater, a carriage, an arm thereon, a heating wire secured on the arm, and means on the arm for securing the wire around the glass to be heated.
6. In an electric glass heater, a heating wire, a support for the wire, and means adjusting the support longitudinally and transversely of the article to be heated.
7. In an electric glass heater, a heating wire, a support for the wire, means adjusting the support longitudinally and transversely of the article to be heated, and means tending to move the support toward the article heated automatically during the heating operation.
8. In an electric glass heater, a trolley, a pair of electric terminals carried thereby, glass heating means connected to the terminals, trolley wires, wires leading from the terminals to the trolley wires, and traveling contact devices connecting the trolley wires with the wires leading to said terminals.
- 30 Signed at Pittsburg, Pa., this 12th day of November 1906.
- 35 JAMES RAMSEY SPEER.
